PENCIL SHARPENER

Howard L. Stover, Bellefonte, Pa., assignor of
one-half to Norval Remick, Lock Haven, Pa.

Application March 22, 1934, Serial No. 716,892

4 Claims. (Cl. 120—93)

This invention relates to pencil sharpeners and more particularly to a pencil sharpener housing employing a conventional safety razor blade as a sharpening means.

5 The principal object of the invention is to provide such a housing, wherein the razor blade is firmly held so as to sharpen a pencil with a smooth clean cut yet the razor blade may be easily removed, reversed and reinserted without dis-

10 turbing any part of the housing.

Another object is to provide a razor blade housing for a pencil sharpener, the housing being so constructed that the hands of the user are protected against cuts and scratches while the 15 device is in use, and so that the razor blade itself is protected against damage to its cutting edge.

Still another object is to provide a very compact pencil sharpener of the type described, but one which will not become clogged by the pencil 20 shavings.

A further object is to provide a housing for a pencil sharpener which may be constructed from a blank of sheet material and may be produced very economically so as to be marketed for 25 a relatively few cents.

Other objects and advantages of this invention will be apparent during the course of the following detailed description, taken in connection with the accompanying drawing, forming a part of this 30 specification and in which drawing:—

Figure 1 is a side elevation of one face of the improved pencil sharpener housing, carrying a safety razor blade, with a conventional pencil shown in dots and dashes as inserted thereinto for 35 sharpening.

Figure 2 is a side elevation of the opposite face of the novel housing, with a razor blade carried thereby.

Figures 3, 4 and 6 are enlarged sectional views 40 substantially on the respective lines in Figure 1.

Figure 5 is an end elevation of the novel pencil sharpener.

Figure 7 is a plan view of a plurality of blanks 45 constituting the pencil sharpener housing.

45 In the drawing, wherein for the purpose of illustration is shown only a preferred embodiment of the invention and wherein similar reference characters designate corresponding parts throughout the several views, the pencil sharpener, as a whole, is designated generally as A, the novel housing as B and the sharpening means as C.

50 The pencil sharpener A, as a whole, is a particularly light weight, metallic article, having a length and breadth not much more than that of the conventional safety razor blades.

The novel housing B is preferably comprised of a single sheet

of the plate portion, as shown particularly in Figure 6, thus closing this end from the indentation 17 to the edge 14. The opposite edges of the plate and clamping portions are not curved over and thus is provided a compartment with a narrow longitudinally extending opening 27 at its side and a transverse opening 28 at its end. It might be said at this point that the clamping portion 22 and its curved section 23 should possess some resiliency.

A guard portion 30 is provided and constitutes the small portion referred to as curved over from the edge 16 so as to overlie a small section of the face 15 to one side of the transverse medial line 15 of the plate portion, as shown in Figures 1 and 3. It is desirable that this guard portion be so disposed that it will present a portion in resilient contact with a razor blade when inserted into the housing, and it will be noted its length is less than one-half the length of the plate portion.

Now as to the pencil guide or cutting head portion 31, this is hollow, and shaped somewhat like a truncated cone, the larger end 32 lying at the edge 13 of the plate portion while the smaller end 33 is short of the guard portion 30 and does not extend beyond the transverse medial line of the plate portion. In the example shown, it falls just short of such line. The side edge 34 of the guide portion 31 is spaced from the plate portion 11 but except for the corrugation 19 a substantially circular end 32 is provided.

Referring to the blank 10 as shown in Figure 7, it will be seen that a substantially rectangular member is provided with an angular wing extending from one side edge, this wing forming the guide portion 31, while there is an indentation 35 adjacent the transverse medial line, this being provided to form one end edge of the guard portion 30. Small indentations 36 are provided to aid in curving the sections 25 and 26 as is apparent.

The housing may be constructed from the blank 10 by curving the clamping portion 22 over the plate portion 11 generally along the dotted line 37, after which the end edges are crimped or curved as at 25 and 26, then the guard portion 30 is curved over the plate portion 11 and substantially along the dotted line 38 and finally the guide portion is produced by curving the angular wing into a substantially truncated conical shape.

It will be seen in Figure 7 that the blank for the housing may be very economically produced with very little loss of material, by the arrangement shown, where a strip of material may be stamped to provide a plurality of the housing blanks.

As for the safety razor blade C, the same is preferably of the type shown in numerous United States Patents, as for example U. S. Patent #228,829, dated June 15, 1880. This conventional safety razor blade includes a flat plate forming the blade proper 40, having a longitudinally extending cutting edge 41 and, enclosing the edge opposite the cutting edge, a channelled member 42 which frictionally holds that portion of the blade 40, forming an enlargement to that portion of the assembly.

In order to employ the improved pencil sharpener, a suitable safety razor blade C is slipped into the mouth 28 until it is wholly within the housing, as shown in Figure 1, with the clamping portion grasping the channelled member 42, the guard member covering what would otherwise be an exposed portion of the cutting edge of the razor blade and much of the cutting edge 41 pro-

jecting into the guide member as shown in Figure 5, with the blade well held by the side edge 34 of the guide portion. It will be noted from Figures 3, 4 and 5 that the cutting edge 41 lies to one side of the axis of the mouth at the smaller end 33 of the guide portion so that a satisfactory cut at the point of the pencil may be had.

A conventional lead pencil when sharpened by this novel pencil sharpener will present a wooden cutting surface to not over one-half of the cutting edge 41 of the razor blade 40, so that, when this one-half of the edge becomes dull the blade may be removed (pressing against the edge of the blade projecting into the indentation 17 will enable the fingers to grasp the blade as it is partly ejected), reversed and reinserted, thus presenting a fresh cutting edge to the pencil. Very little dulling of the cutting edge is, of course, produced by the lead of the pencil.

Ground off lead and pencil shavings will find their way from the sharpener thru the corrugation 19 and slot 20 and will not remain to clog the device nor dull the blade.

The blade is held firmly and will not be apt to slip nor vibrate when being used. It is so protected that the hands of the user of the device will not come into contact with the cutting edge of the blade. In fact, the device may be carried in the pocket, a pencil box or the like without injury or damage to the person, clothing or the blade itself.

Various changes may be made to the form of invention herein shown and described, without departing from the spirit of the invention or the scope of the claims.

What is claimed is:

1. In a safety-razor-blade-type pencil sharpener housing, an elongate plate portion, razor blade clamping means at one side edge of said portion, a guard portion overlying a face of said plate portion at the opposite side edge thereof and extending short of one end edge of said plate portion, and a hollow, substantially truncated conical guide portion overlying a section of said face at said last named side edge, said guide portion being spaced from said guard portion and with the smaller end of said guide portion facing said guard portion, said guide portion lying to one side of the transverse medial line of said plate portion and having a side edge spaced slightly from said plate portion.

2. In a safety-razor-blade-type pencil sharpener housing, an elongate plate portion having a depression extending longitudinally thereof and to a side edge thereof, a razor blade clamping portion of resilient material overlying said depression and spaced therefrom, and a hollow, substantially truncated conical guide portion overlying a section of said plate portion and extending from the opposite side edge of said plate portion, said guide portion having a side edge, spaced from said last named side edge and spaced slightly from said plate portion.

3. In a safety-razor-blade-type pencil sharpener housing, an elongate plate portion having a corrugation and a slot both extending longitudinally thereof adjacent one side edge, said slot disposed within said corrugation and extending short of the end edges of said plate portion, razor blade clamping means at the other side edge of said plate portion, a guard portion disposed along a section of the first named edge and overlying a section of said plate portion, and pencil end guiding means including a substantially truncated conical guide portion extending over a section of

said plate portion with a side edge of said guide portion facing said plate portion close adjacent said corrugation and slot.

4. A blank for a pencil sharpener housing comprising a metallic sheet having substantially parallel end edges, a side edge forming substantially a right angle with either of said end edges,

the opposite side edge of said sheet paralleling a portion of the first named side edge from an end edge, then being indented, adjacent the transverse medial line of said sheet, said sheet continuing from said indentation in an angular wing extending away from said first named side edge. 5

HOWARD L. STOVER.
